DESIGN.

No. 35,644.

M. T. GOLDSMITH.
ALPHABET.

Patented Jan. 28, 1902.

(Application filed Dec. 26, 1901.)

UNITED STATES PATENT OFFICE.

MARCUS T. GOLDSMITH, OF NEW YORK, N. Y.

DESIGN FOR AN ALPHABET.

SPECIFICATION forming part of Design No. 35,644, dated January 28, 1902.

Application filed December 26, 1901. Serial No. 87,374. Term of patent 7 years.

To all whom it may concern:

Be it known that I, MARCUS T. GOLDSMITH, a subject of the Czar of Russia, and a resident of the city of New York, borough of Manhattan, in the county and State of New York, have invented and produced a new and original Design for an Alphabet, of which the following is a full, clear, and exact description.

My invention relates to a design for an alphabet to be used for decorative and advertising purposes.

The drawing illustrates the form of a complete set of capital letters, both in outline and in longitudinal section, the section being taken, for example, through the letter "Z" on the line 1 1.

The leading feature of my design consists of the form of the letters as shown and which presents to the eye a new and attractive appearance.

Having thus described my invention, I claim as new and desire to secure by Letters Patent—

The design for the alphabet herein shown and described.

In testimony whereof I have signed my name to this specification in the presence of two subscribing witnesses.

MARCUS T. GOLDSMITH.

Witnesses:

THEO. G. HOSTER,
EVERARD B. MARSHALL.
